RETRACTABLE CAR COUPLER

William J. Metzger, East Cleveland, Ohio, assignor to National Malleable and Steel Castings Company, Cleveland, Ohio, a corporation of Ohio

Application August 9, 1947, Serial No. 767,814

14 Claims. (Cl. 213—5)

1

This invention relates to car couplers and more particularly to a retractable coupler adapted for use in the front end of a locomotive.

An object of my invention is to provide a retractable car coupler arrangement which permits the coupler to be moved easily and quickly from normal operating position to inoperative position within the locomotive pilot contour.

Another object is to provide a vertically swingable retractable coupler utilizing spring means in a novel manner to counterbalance the coupler.

A further object is to provide a retractable coupler which is mounted for swinging about a horizontal axis from normal operating position to lowered inoperative position, the coupler carrying a novel spring arrangement for counterbalancing the coupler about its horizontal pivot.

In the past retractable couplers of the type which are adapted to swing about a horizontal axis from operative to inoperative position have usually employed a counterweight on the coupler shank to facilitate swinging of the coupler to and from operating position. A counterweighted coupler shank is necessarily heavy and bulky and occupies space within the locomotive pilot which could be used to advantage to accommodate train service lines. It adds to the weight of the front end of the locomotive and generally requires a special pilot construction to receive the counterweighted end of the coupler. My invention eliminates the counterweights on couplers of this type by providing a spring arrangement which counterbalances the coupler head. The invention permits the use of a comparatively short shank coupler of minimum width shank, the entire assembly occupying very little space. The springs for counterbalancing the coupler are preferably positioned to react at one end against a seat on the coupler shank and at the other end against a seat on a support member which pivotally mounts the coupler. The spring seats are pivotally connected to their respective parts and are so positioned that the moment arm of the spring expansive force about the horizontal pivot of the coupler varies from a maximum in the normal operating position of the coupler to a minimum in the retracted position thereof. Simultaneously the magnitude of the expansive force of the spring increases from a predetermined value at the normal operating position of the coupler to a maximum at the retracted position.

Through this arrangement the moment tending to balance the coupler head decreases approximately in proportion to the moment necessary to balance the coupler in all its positions from operative to retracted.

2

Other objects and advantages of my invention will be apparent from the following description taken in conjunction with the drawings in which:

Fig. 1 is a plan view of an embodiment of the invention.

Fig. 2 is an elevational view, partly in vertical section, of the embodiment shown in Fig. 1.

Fig. 3 is an elevational view, partly in section, showing the coupler in lowered or retracted position.

Fig. 4 is a transverse sectional view taken along line 4—4 of Fig. 2.

Fig. 5 is a longitudinal vertical sectional view of a modification of the invention.

Referring to the drawings the outline of the front end of a locomotive is shown in dot-dash and is indicated by the reference numeral 10. Also shown in dot-dash within the locomotive pilot is the flexible type support 11 for the coupler 12 and its associated parts to enable vertical angling of the coupler. A member 14 directly engages support 11 and comprises a forwardly extending bifurcated portion having arms 15 and a rearwardly extending portion having a pair of spaced ears 16. Ears 16 are provided with aligned vertical openings 17 for reception of a pin (not shown) for pivotally connecting member 14, preferably, to a conventional yoke member having a cushioning mechanism associated therewith in a manner well known in the art. It is to be understood, however, that member 14 may be pivotally connected directly to the locomotive pilot structure without departing from the spirit of the invention. In either case horizontal angling of the coupler 12 is provided. The coupler, which is of the conventional knuckle type now in service, has a shank 20 which is received between arms 15 and is pivotally connected thereto for vertical swinging by means of a horizontal pin 22. Thus the coupler is adapted to be swung about pin 22 downwardly from normal operating position to lowered or retracted position within the locomotive pilot contour as shown in Fig. 3. Pin 22 is maintained in position by means of lug 24 on one of arms 15, overlapping one end of the pin and by a vertical bolt 25 adjacent the other end of the pin. Bolt 25 extends through lugs 26 and is locked thereto by means of nuts 27.

The end of coupler shank 20 is recessed as at 30 for receiving a level 31 which is pivotally connected at its lower end to the shank by means of horizontal pin or bolt 32. The upper end of lever 31 is forked as at 33 and pivotally connected thereto is a seat member 34 which is engaged by one end of springs 35. Member 34 has a lug 36 which is received between arms 33 of lever 31.

and is pivotally connected thereto by means of bolt 37. The other end of springs 35 engage another seat member 40 pivotally connected to member 14. Bridging the top sides of the forward ends of arms 15 is a tie member 41 having a pair of spaced rearwardly extending lugs 42. Seat member 40 has a lug 43 received between lugs 42 and a bolt or rivet 44 extending through these lugs enables rotation of the member. Springs 35 are maintained on their respective seats by means of a plunger 45 on seat member 40 which is slidably received in sleeve 46 extending from seat member 34. This sleeve and plunger arrangement precludes springs 35 from bending or twisting during compression thereof as the coupler is swung downwardly to inactive position.

It will be observed in Fig. 2 that the reaction of springs 35 against seat members 34 and 40 tends to pivot the coupler in a counterclockwise direction. The initial compression applied to springs 35 is preferably of such an amount as will just balance the coupler in horizontal position. The initial compression can be adjusted by means of a pair of bolts 48 which extend through lever 31 and lugs 49 on coupler shank 20. By screwing nuts 50 on bolts 48 seat member 34 will be moved closer to seat member 40 and thereby increase the compression of springs 35.

The moment arm of the spring force about pivot pin 22 is designated as "a." In the normal horizontal position of the coupler (Fig. 2) moment arm "a" is a maximum while the expansive force of the springs is at a minimum and is equal to the initial compression applied thereto. As the coupler is swung downwardly toward inactive position it will be apparent that springs 35 will pivot about bolt or rivet 44 in a clockwise direction so that moment arm "a" of the spring force will simultaneously decrease. Thus, as the springs approach a vertical position during lowering of the coupler, moment arm "a" will approach a minimum. It will also be observed that as the coupler is lowered, seat members 34 and 40 move closer together, thereby further compressing springs 35. At a point just before the coupler reaches fully lowered position the moment arm "a" is zero while the spring compression is a maximum. This occurs when the centers of bolt 37, rivet 44 and pin 22 lie in a straight line. Lowering of the coupler from this point to its final position within the confines of the pilot results in a slight increase of the moment of the spring force as indicated at "b" in Fig. 3 and a slight decrease in the spring compression.

It will be observed that in fully lowered position of the coupler the line of force of the spring passes to the left side of pivot pin 22 (as viewed in Fig. 3) and therefore the action of the spring is to tend to rotate the coupler clockwise. This serves to maintain the coupler in lowered position after it swings downwardly past the point where the moment arm of the spring force is zero and thus prevents any tendency of the coupler to swing or bounce upwardly while in retracted position.

The counterbalancing of the coupler by the springs in substantially all of its positions from operative to lowered within the pilot contour constitutes an important feature of the invention. It enables a workman either to raise or lower the coupler safely with a minimum of time and effort. Also this feature permits a shorter overall length of the coupler assembly than if a counterweighted coupler were used while also permitting a reduction in the width of the coupler shank and a sub-

stantial decrease in the overall weight of the unit.

The underside of arms 15 are connected by a transverse wall 54 the end surface 55 of which forms a stop for limiting downward swinging of the coupler into the pilot. When the coupler is swung upwardly from retracted position, engagement between coupler shank 20 and wall 54 positions the coupler in approximately normal operating position. Shank 20 is recessed as at 56 to accommodate springs 35 as the coupler is swung from normal operating position to retracted position.

The coupler is locked in normal operating position by means of a pin 57 positioned rearwardly of pivot pin 22 and extending through shank 20 and arms 15 of member 14. Pin 57 is precluded from accidentally sliding out of position by a vertical bolt 58 located adjacent the end of the pin head 59 and passing through lugs 60 on arms 15. A removable hook 61 received in opening 62 in bolt 58 precludes accidental withdrawal of the bolt from lugs 60.

To retract the coupler, hook 61 is removed and bolt 58 and pin 57 are withdrawn. By applying a comparatively light downward force to the coupler head the latter may be easily swung to the retracted position shown in Fig. 3. Pin 57 may now be reinserted and secured in position as before by means of bolt 58 and hook 60. The coupler is now locked in retracted position. Pin 57 thus serves effectively to lock the coupler in either horizontal or lowered position.

To raise the coupler from lowered or retracted position to horizontal operating position the reverse steps of the preceding operation are carried out. It is to be noted that a comparatively light upward force applied to the coupler head will raise it to operating position.

Referring to the modification of my invention shown in Fig. 5 the spring 70 for counterbalancing the coupler 12' is carried within recess 71 in coupler shank 20'. At the lower rearward end of recess 71 is a spring seat member 72 pivotally connected to support member 14' by means of a horizontal pin 73. Another spring seat member 74 within recess 71 is pivotally connected to a rearwardly extending arm 75 on member 14'. Spring 70 reacts between members 72 and 74 to counterbalance the coupler in a manner similar to that of the previous embodiment. Seat members 72 and 74 are maintained with their spring abutment surfaces parallel and in line throughout movement of the coupler from horizontal to retracted position by means of sleeve 78 on member 72 and plunger 79 on member 74 slidably received in the sleeve. With this sleeve and plunger arrangement spring 70 will compress and expand along its axis without any tendency to bend or be distorted.

The coupler is pivotally connected to member 14' by horizontal pin 80 to permit the coupler to be lowered to inactive position within the pilot. A removable pin 82 positioned forwardly of pin 80 and extending through member 14' and shank 20' locks the coupler in horizontal position. Upon withdrawal of pin 82 and lowering of the coupler the pin may be reinserted in member 14' to lock the coupler in retracted position as may be seen in Fig. 5, the coupler and spring mechanism being shown in dot-dash in this position. Any suitable means for retaining pins 80 and 82 in place may be used.

The operation of the device is similar to that of the previous embodiment. The moment arm

of the spring force about pin 80 is a maximum when the coupler is in operating position. Spring 70 is preferably of such size and capacity as will just balance the coupler in horizontal position. As the coupler is swung to retracted position the moment arm of the spring force decreases and simultaneously the compression of the spring between seat members 72 and 74 increases. At a point just before the coupler is fully retracted the amount arm of the spring force has decreased to zero while the compression applied to the spring is a maximum. Movement of the coupler from this point to its fully retracted position is now assisted by the spring as the moment arm of its force about pin 80 has reversed whereby the force now acts in a clockwise direction. This feature, therefore, serves to maintain the coupler in fully retracted position, and yet does not make subsequent raising of the coupler difficult because the actual distance the coupler must be swung upwardly, before the spring force begins to act in a counterclockwise direction to raise the coupler, is very slight.

As in the previous embodiment the coupler is counterbalanced by the spring in substantially all positions from horizontal to lowered and only a comparatively light force applied to the coupler head is needed to raise or lower the coupler. The modification, however, is particularly adapted for use where a minimum of space is available in the pilot structure.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

What I claim is:

1. In a locomotive pilot a member supported therein, said member having a pair of forwardly extending arms, a car coupler having a shank received between said arms, said shank being pivotally connected to said arms to enable vertical swinging of said coupler from horizontal operating position to lowered position within the pilot contour, a pivotal spring-abutment member on said first-named member positioned substantially in vertical alignment with and spaced from the pivotal axis of said coupler, another pivotal spring-abutment member at the end of said shank, and spring means reacting between said spring-abutment members for substantially counterbalancing said coupler, said spring-abutment members being so arranged that the moment of the line of force of said spring means is a maximum when said coupler is in horizontal operating position, said spring means during swinging of said coupler to lowered position being adapted to pivot about said coupler supporting member to a position in which said moment is a minimum, and simultaneously said pivotal spring-abutment member on said shank being moved toward said pivotal spring-abutment member on said coupler carrying member to progressively increase the compression of said spring means.

2. In a locomotive pilot a member for carrying a car coupler, a coupler having a shank pivoted to said member about a horizontal axis and adapted to swing from horizontal operating position downwardly to inoperative position within the pilot, and spring means disposed longitudinally of said member for counterbal-

ancing said coupler, one end of said spring means being pivotally mounted with respect to said member, the other end of said spring means being pivotally mounted with respect to said shank, said spring means being so arranged that upon swinging of said coupler from horizontal operating position to inoperative position said spring means is compressed and simultaneously is swung about said coupler carrying member from a position in which the moment arm of its line of force about said horizontal axis is a maximum to a position in which the moment arm is zero at a point just before the coupler moves to its lowermost position within the pilot.

3. In a locomotive pilot a member for carrying a car coupler, a coupler having a shank pivoted to said member about a horizontal axis and adapted to swing from horizontal operating position downwardly to inoperative position within the pilot, pivotally mounted spaced spring-abutment means on said coupler shank and member, and spring means reacting between said abutment means to urge said coupler toward horizontal operating position, said abutment means being so arranged as to move relatively toward one another to compress said spring means as said coupler is swung downwardly toward inoperative position and simultaneously to move said spring means from a position in which the moment arm of the line of force of said springs about said axis is a maximum to a position in which the moment arm is zero.

4. In a locomotive pilot a member for carrying a car coupler, a coupler having a shank pivoted to said member about a horizontal axis and adapted to be swung from horizontal operating position downwardly to inoperative position within the pilot, a lever extending upwardly from said shank adjacent the end of the latter, a spring-abutment member pivoted to the upper end of said lever, another spring-abutment member disposed forwardly of said first-named spring-abutment and being pivoted to said coupler carrying member, and spring means reacting between said spring-abutment members to substantially counterbalance said coupler in all positions from operating to retracted.

5. In a locomotive pilot a member for carrying a car coupler, a coupler having a shank pivoted to said member about a horizontal axis and adapted to be swung from horizontal operating position downwardly to inoperative position within the pilot, a lever extending upwardly from said shank and being secured thereto for limited pivotal movement in a longitudinal direction, a spring-abutment member pivoted to the upper end of said lever, another spring-abutment member pivoted to said first-named member and disposed forwardly of said spring-abutment member on said lever, and spring means reacting between said spring abutment members to counterbalance said coupler, and means for adjusting the position of the upper end of said lever in a longitudinal direction for varying the initial compression applied to said spring means.

6. In a locomotive pilot a member supported therein, said member having a pair of forwardly extending arms, a car coupler having a shank received between said arms, said shank being pivotally connected to said arms to enable vertical swinging of said coupler from horizontal operating position to lowered position within the pilot contour, a tie member joining the forward end of said arms above said shank, a forward pivotal member mounted on said tie member, a rearward

pivotal member mounted on said shank, and spring means reacting between said pivotal members for substantially counterbalancing said coupler in all positions from horizontal to lowered, said pivotal members being so arranged that the moment arm of said spring force is a maximum when said coupler is in horizontal position and decreases as the coupler is lowered, and simultaneously said spring is progressively further compressed as said coupler is lowered.

7. In a locomotive pilot a member for carrying a car coupler, a coupler having a shank pivoted to said member about a horizontal axis and adapted to swing from horizontal operating position downwardly to inoperative position within the pilot, said shank being recessed rearwardly of said axis, a seat member in the rearward end of said recess and pivoted to said shank, another seat member pivoted to said first-named member and extending into the forward end of said recess, and spring means within said recess and reacting between said seat members to substantially counterbalance said coupler, said seat members being so disposed that the distance of the line of force of said spring means from said axis is a maximum when the coupler is in horizontal position and progressively decreases to a minimum as the coupler is lowered to inoperative position, and simultaneously said seat member on said shank is adapted to move toward said other seat member to progressively further compress said spring means.

8. In a locomotive pilot a member for carrying a car coupler, a coupler having a shank, a horizontal pivot pin connecting said shank to said member to permit swinging of the coupler from horizontal operative position to lowered inactive position, said shank being recessed rearwardly of said pin, a seat member in the rearward end of said recess and pivoted to said shank, a forward seat member pivoted to said first-named member and extending into said recess, spring means reacting between said seat members to substantially counterbalance said coupler from horizontal operative position to lowered inactive position, and guide means on said seat members for maintaining said seat members in proper alignment.

9. In a retractable car coupler arrangement a member for carrying a car coupler, a coupler having a shank, a horizontal pivot pin connecting said shank to said member to permit vertical swinging of the coupler, a spring seat member pivoted to said first-named member at a point substantially directed above said pin, another spring seat member pivoted to the end of said shank at a point rearwardly of said first-named seat member, spring means under initial compression between said seat members for substantially counterbalancing said coupler in a position from horizontal operative to lowered inactive, and slidably engaging guide means on said seat members for maintaining said seat members in proper alignment.

10. In a retractable car coupler arrangement a member for carrying a car coupler, a coupler having a shank, a horizontal pivot pin connecting said shank to said member to permit the coupler to swing from horizontal operating position downwardly to retracted position, a removable pin extending through said member and shank for locking the coupler in operating position, said pin being adapted to be removed to allow the coupler to be swung downwardly to retracted position and then reinserted into said member to lock the coupler in the retracted posi-

tion, pivotally mounted spaced spring-abutment means on said shank and member, and spring means reacting between said abutment means for substantially counterbalancing the coupler from horizontal operating position downwardly to retracted position, said spring-abutment means being so arranged as to be moved into closer relationship as said coupler is retracted to progressively increase the compression of said spring means.

11. In a locomotive pilot a member for carrying a car coupler, a coupler having a shank pivoted to said member about a horizontal axis and adapted to swing from horizontal operating position downwardly to inoperative position within the pilot, and longitudinally extending resilient means disposed above said shank for counterbalancing said coupler, one end of said resilient means being pivotally associated with said member, the other end of said resilient means being pivotally associated with said coupler shank, said shank having a recess adjacent said resilient means, said resilient means, during swinging of said coupler from horizontal position downwardly to inoperative position, being rotated about said member and received in said recess.

12. A car coupler mounting for a locomotive for enabling movement of the coupler from a horizontal operative position to a lowered inoperative position, said mounting comprising a member carried by the locomotive, a horizontal pin extending through the shank of said coupler and being secured to said member, a pivotally mounted spring-abutment carried by said member at a point spaced from said pin, a second pivotally mounted spring abutment carried by said coupler and spaced longitudinally from said first-named abutment when said coupler is in operative position, spring means compressed between said abutments and tending to lift said coupler toward a horizontal position, said second-named abutment being so located on said coupler relative to said pin and said first-named abutment as to move toward said first-named abutment as said coupler is moved to its lowered inoperative position, whereby said spring is further compressed and its direction of force is so altered as to maintain said coupler substantially counterbalanced during its movement from operative to inoperative position.

13. A retractable car coupler arrangement adapted for mounting in a railway vehicle, comprising a member for carrying a car coupler, a car coupler having a shank pivotally connected to said member about a horizontal pivot pin and being adapted to be swung from horizontal position to retracted inoperative position, a pivotally mounted spring abutment on said coupler carrying member disposed substantially in vertical alignment with said pin and spaced therefrom, a second pivotally mounted spring abutment carried by said shank and spaced longitudinally from said first-named spring abutment, spring means compressed between said spring abutments for exerting a force against said shank which tends to substantially counter-balance said coupler in horizontal position, said spring abutment on said shank being movable with said shank as said coupler is swung to a retracted position to cause said spring means to pivot with said first-named abutment about said member to a position in which the line of force of said spring means passes through said pin and simultaneously said spring abutment on said coupler carrying member to further compress said spring means.

14. A retractable car coupler arrangement adapted for mounting in a railway vehicle, comprising a member for carrying a car coupler, a car coupler pivotally connected to said member about a horizontal pivot pin and being adapted to be swung from horizontal position to retracted inoperative position, pivotally mounted spring abutment carried by said coupler carrying member, said spring abutment being spaced in a given fixed direction from said pin, a second pivotally mounted spring abutment carried by said coupler, and spring means compressed between said spring abutments, said second-named spring abutment being spaced from said first-named spring abutment and being so disposed that when the coupler is in horizontal position the line of force of said spring means against said spring abutments is substantially at right angles to said given fixed direction in which said first-named spring abutment is spaced from said pin, the force exerted by said spring means against said coupler tending to counterbalance said coupler in horizontal

position, said spring abutment on said coupler being rotatable with said coupler during swinging of said coupler to retracted position to pivot said spring means about said coupler carrying member to a position in which the line of force of said spring means passes through said pin, and simultaneously said spring abutment on said coupler is moved progressively toward said spring abutment on said coupler carrying member to further compress said spring means.
